UNITED STATES PATENT OFFICE.

WILLIAM L. HAGEN, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

DESIGN FOR A TRUNK LOCK.

Application filed January 9, 1922. Serial No. 126. Term of patent 7 years.

To all whom it may concern:

Be it known that I, WILLIAM L. HAGEN, a citizen of the United States, and a resident of New Britain, in the county of Hartford and State of Connecticut, have invented a new, original, and ornamental Design for Trunk Locks, of which the following is a specification, reference being had to the accompanying drawings, forming part thereof, in which—

Figure 1 is a face view of a trunk lock showing my improved design.

Figure 2 is a sectional view of the same on a plane denoted by the dotted line 2—2 of Figure 1.

I claim:

The ornamental design for a trunk lock shown in the accompanying drawing.

WILLIAM L. HAGEN.
